UNITED STATES PATENT OFFICE.

ALFRED L. RUTHVEN, OF ROCHESTER, NEW YORK.

SIMPLEX TRAIN CONTROL.

Application filed March 13, 1922. Serial No. 543,807.

To all whom it may concern:

Be it known that I, ALFRED L. RUTHVEN, a citizen of United States, residing at Rochester, in the county of Monroe and 5 State of New York, have invented certain new and useful Improvements in Simplex Train Controls, of which the following is a specification, reference being had therein to the accompanying drawing.

10 The present invention relates to train controlling apparatus, and is more particularly an improvement over the apparatus disclosed in my copending applications filed January 14, 1921, Serial No. 437,288 15 (now U. S. Patent No. 1,470,108, dated Oct. 9, 1923), and filed September 6, 1921, Serial No. 498,609.

It is the object of the invention to provide a train control apparatus of the general kind disclosed in the above-mentioned applications, and improved generally in the several devices and details forming component parts of the apparatus.

One of the more specific objects of the invention is the provision of means whereby when a caution signal or similar impulse is received by the vehicle equipment, the vehicle must slow down below a predetermined speed of say fifteen miles per hour, 20 and is prevented from running above such speed for a given distance, such as a block, in order that the caution or similar condition be maintained through the block or predetermined distance of the track.

Another object is the provision in the rail or rails of the track of isolated or insulated sections, instead of simply insulated joints as disclosed in the aforesaid applications, 30 with means for connecting and disconnecting said isolated sections with the main portions of the rail or rails, in order that the insulated joints or insulation may be bridged and unbridged for the control of vehicle equipment in passing the isolated rail sections, and such means also connecting the 40 longer sections of the rail or rails across or by bridging the short isolated sections, in order that the rail or rails may be used as part of track circuits if necessary or desirable, without interference by the insulated joints.

A further object is the provision of novel means for installing or attaching the vehicle equipment as a unit to a locomotive 50 or car, in order that the vehicle equipment

may be readily installed on the locomotive or car for cooperation with the track equipment and for controlling the vehicle.

A further object is the provision of a novel insulated rail joint including the isolated or insulated rail section.

A still further object is the provision of an insulated rail joint with means for detecting or indicating a break-down of the insulation.

Another object is to provide means whereby the break-down of insulation of one of the insulated rail joints or isolated rail sections will control the bridging means of one or more other insulated joints or isolated rail sections, to assure of a signal being transmitted to the vehicle equipment, and whereby the break-down of the rail insulation will be detected or indicated as well as avoiding the possibility of the failure of caution or danger signals or conditions being established in the vehicle equipment.

Still another object is to provide means in rear of the sand applying means of the locomotive or car and in advance of the 80 wheels or contact members of the vehicle circuit for removing the sand from the rail or rails, whereby to avoid such wheels or contact members from being insulated from the rail or rails by the sand, so as to avoid 85 false signals being given, which would occur should the vehicle circuit be broken by the insulating effect of the sand.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a diagrammatical view of the vehicle or train equipment.

Fig. 2 is a plan view of the ratchet device of such equipment.

Fig. 3 is a fragmentary side elevation of a locomotive showing the equipment installed and also the sand removing means, 105 portions being broken away and portions shown in section.

Fig. 5 is a plan view of the vehicle equipment unit which is attached to the locomotive or car, portions being shown in section.

6 Fig. 6 is a plan view of one of the insulated rail joints including the isolated rail section, showing portions of the electrical circuits diagrammatically.

10 Figs. 7 and 8 are enlarged cross sections on the respective lines 7-7 and 8-8 of Fig. 6.

Fig. 9 is a perspective view of one of the sand-removing scrapers.

15 Fig. 10 is a diagrammatical view of the track equipment and circuits.

Fig. 11 is a fragmentary diagrammatical view of the track equipment showing a modification.

20 Fig. 12 is a diagrammatical view showing a modified form of caution-maintaining device.

The track part of the apparatus employs the traffic rails R, although special control rails or conducting means can be used if desired, but such special rails are unnecessary inasmuch as the traffic rails will suffice in most instances. As shown, the two pairs of wheels W and W' travel on the rails R, and these wheels may be the wheels of the locomotive, tender or one or more cars, or may be special contact members. As shown, the wheels W belong to the locomotive (reference being had to Fig. 3) while the wheels W' are those of a special unit attached to the locomotive, as will hereinafter more fully appear. The two pairs or sets of wheels are insulated from one another, as at 7, and a vehicle control circuit 8 has its terminals connected to the two sets of wheels so that said circuit will normally be closed whenever either or both of the rails R are electrically continuous between the wheels W and W' at the corresponding side or sides. It will be noted that by connecting the terminals of the circuit 8 to the axles of the wheels W and W', the circuit will be closed by both rails of the track, so that the possible insulation of the wheels from one rail, by sand, ice or other insulating matter on the rail, will not permit the circuit to open, inasmuch as the other rail also completes the circuit between the opposite wheels. This provides double assurance against the accidental opening of the train control circuit.

The control circuit 8 is opened or broken by the provision of insulated joints in both rails at control stations arranged in pairs, and each including an isolated rail section 9 insulated, as at 9', from the longer sections of the rails. When the insulated wheels or contact members W' move on the isolated rail sections 9 which are disconnected electrically from the main rail sections, the 55 insulation 9' will break the circuit 8. The

wheels W not being insulated from the other wheels of the locomotive or vehicle, will prevent the circuit 8 from being broken more than once as the wheels W and W' pass over one pair of isolated rail sections 9. Thus, when the wheels W are on the pair of isolated sections 9, such wheels are electrically connected with the other wheels of the car or train through the trucks and metal parts of the locomotive and tender, thereby still completing the circuit 8 through the main rail sections, and only when the wheels W' move on the isolated sections 9, with the bridging means open, is the circuit 8 broken. Any suitable number of pairs of isolated rail sections 9 or insulated joints in the rails R can be provided in series or suitably-spaced intervals at a control station or portion of the track, whereby the vehicle or train in moving along the track and passing over the isolated rail sections 9 in succession, will break the circuit 8 one or more times, according to the conditions. As shown in Fig. 10, there are two pairs of isolated rail sections 9 at the entrance to the block or between adjacent blocks, and a similar set of isolated rail sections located intermediate the ends of the block for repeating the control as the vehicle is passing through the block, the block, as shown in Fig. 10, being the distance between the wayside semaphores S.

In order to control the vehicle equipment from the track, under the traffic or other conditions, one isolated rail section 9 of each pair is bridged by a suitable switch 10 with the main rail sections, which are bridged or connected across the isolated sections 9 by the conductors 15, thereby making the main or long rail sections electrically continuous, whereby they can, if desired or necessary, be used as parts of track circuits. The switch 10 electrically connects the isolated rail sections 9 with the conductor 15, thereby bridging the insulation 9', in which event the circuit 8 of the vehicle equipment is not opened when the wheels W' pass on said isolated rail sections, but when the switch 10 is open, this disconnects the isolated rail section from the main rail sections, so that the vehicle circuit will be broken when the wheels W' pass over the isolated rail sections. The bridging means is only required for one rail, although it can be duplicated for both isolated rail sections of the two rails, but the one bridging means will suffice, inasmuch as the circuit 8 will also be broken at the opposite side of the track if the bridging means at one side is opened. The bridging switches 10 of the several isolated rail sections can be operated by any suitable means. As shown, electromagnets 11 are employed for holding the switches 10 closed, and the switches will open automatically if the mag-

nets are deenergized, either intentionally or by the failure of the track equipment, thereby providing a positive breaking or opening of the circuit 8 when the wheels pass over 5 the isolated rail sections.

Coming to the vehicle equipment of which the circuit 8 and contact wheels W and W' are a part, such circuit is energized by an electrical generator 16 or other source of 10 electrical current, thereby energizing, when the circuit is closed, the electromagnets 17 and 18 of a responsive ratchet device 19 for producing caution and danger signals or conditions, or such other signals or conditions as may be desired or required. The 15 circuit 8 includes in series the wheels W, cup 56, pawl 34, armature lever 33, electromagnets 54, 17 and 18, left hand detector plate 57, generator 16, right hand detector 20 plate 57 and wheels W', the parts 33, 34, 54, 56 and 57 being described more in detail hereinafter. As shown, the device 19 controls a caution electromagnet or device 20 and a danger electromagnet or device 21. 25 The magnets 20 and 21 are disposed in the respective conductors 22 and 23, and said magnets can operate suitable signal members or controlling devices, such as disclosed in my copending applications Serial Nos. 30 215,300 and 257,336 filed February 4, 1918 and October 8, 1918, respectively (now U. S. Patents No. 1,372,457; dated March 22, 1921, and No. 1,374,954, dated April 19, 1921, respectively), although any suitable signaling or controlling devices may be controlled by the device 19. For purpose of illustration, pivoted armatures 24 and 25 for the magnets 20 and 21 are provided, which are normally attracted to said magnets, when 35 they are energized, and when the magnets are deenergized said armatures will swing or drop to give caution and danger signals or to produce corresponding conditions, respectively.

40 The ratchet device 19 is responsive to track conditions for controlling the vehicle equipment accordingly, and includes a ratchet wheel or drum 26 having a segment 27 normally engaged by a contact 28 to which the conductor 22 leads. A second wheel 26' is rotatable with the wheel 26 and has a segment 29 normally engaged by a contact 30 to which the conductor 23 leads. The arrangement is such, that when the 45 wheels are advanced one step, the segment 27 is removed from the contact 28, thereby opening the circuit (described in detail hereinafter) through the magnet 20 whereas the segment 29 still engages the contact 30, but when the wheels are advanced another step, the segment 29 is also removed from the contact 30, thereby also opening the circuit (hereinafter described) of the magnet 21. In this manner, the signalling or controlling 50 devices are operated in succession for pro-

ducing a caution signal or condition first and then a danger signal or condition, so that a series of signals or conditions are obtained in progressive succession, as the device 19 is advanced or moved step by step. 70

The ratchet wheel 26 and secondary wheel 26' are mounted for rotation on a shaft 31, and a suitable spring 32 or other means serves to turn the wheels to original or initial position when the wheel 26 is released to 75 automatically restore the caution and danger signalling or controlling devices by closing the circuits of the magnets 20 and 21. The shaft 31, to which the segments 27 and 29 are electrically connected, is connected by a conductor 22' with the circuit 8 between the magnet 18 and generator 16, and the magnets 20 and 21 are connected by the conductor 23' with the circuit 8 so that the magnets 20 and 21 receive current from the generator without being affected by the breaking of the circuit 8 between the wheels W and W'. The circuit of the caution magnet 20 includes the conductor 23', generator 16, part of circuit 8 through left hand detector plate 57, conductor 22', shaft 31, segment 27, contact 28, one of the conductors 22 leading to one of the contacts 62, a switch 63, the other contact 62, magnet 64 and the other conductor 22. The circuit of the danger magnet 21 includes a switch 55, conductor 23', generator 16, part of circuit 8 through the left hand detector plate 57, conductor 22', shaft 31, segment 29, contact 30 and conductor 23. 90

95 The electromagnet 17 in the main vehicle circuit 8 serves the purpose of advancing the wheel 26 step by step as the circuit 8 is opened and closed in succession. Thus, an armature lever 33 is attracted by said magnet 17 and when the magnet is deenergized said lever drops. A gravity pawl 34 is pivoted to the lever 33 to swing by gravity against the wheel 26, and said wheel has the notches or teeth 35 and 36 for the successive engagement of said pawl. The pawl 34 carries an armature 37 under the influence of the electromagnet 18, which magnet serves to release the pawl from the ratchet wheel when the wheel has been advanced a step. The pawl swings by gravity against the wheel 26 when the magnet 18 is deenergized. Normally, the armature lever 33 is attracted by the magnet 17 and the pawl 34 attracted by the magnet 18, when the circuit 8 is normally closed, and when the circuit is broken, either intentionally or accidentally, or should the current fail, the magnets 17 and 18 are deenergized, thereby releasing both the lever 33 and its pawl 34. Such lever will drop and the pawl engage the notch or tooth 35, and when the circuit 8 is again closed, the lever 33 is attracted by the magnet 17 thereby turning the wheel 26 one step, and when the step is completed, the pawl 34 100

105

110

115

120

125

130

moving with the lever 33 will swing the armature 37 thereof in close proximity with the pole of the magnet 18, so that said pawl is attracted to the magnet 18 and disengaged 5 from the wheel 26, thereby providing for the advance of the wheel 26 and the releasing of the pawl 34 with one operation.

Means are provided for holding the wheel 26 when advanced one or more steps, so as 10 to maintain the signalling or controlling conditions dependent on those conditions, and, for this purpose, a pair of catches or detents 39 and 40 are pivotally mounted to bear against the periphery of the wheel 26, 15 and said wheel has a notch or tooth 41 for the engagement of the catch 39 when said wheel is advanced one step as above described. The wheel 26 has a second notch or tooth 42 for the engagement of the catch 40 when 20 the wheel is advanced a second step, should the circuit 8 be broken or opened the second time, resulting in the repetition of the operation of the lever 33 and its pawl 34, during which the pawl 34 will engage the second notch or tooth 36 to advance the wheel 25 the second step.

The restoration to normal conditions is controlled by the speed or motion of the vehicle, thereby requiring certain conditions as to 30 the movement of the vehicle to be complied with before normal conditions are restored. For this purpose, a governor 43 is provided, being operated according to the speed of the vehicle, and said governor is mounted 35 on a shaft 44 which is operatively connected, by any suitable means, as at 45, with one of the wheels of the vehicle. Said governor has a slide or plate 46 slid up and down by the governor when the speed of the vehicle 40 is increased and decreased, respectively. The catches 39 and 40 have portions 48 and 49, respectively, provided with the slots 50 and 51 receiving pins or studs 52 and 53 carried by the plate 46. The slot 50 is of such a 45 length that when the vehicle is travelling at caution speed, of say fifteen miles per hour or under, the pin 52 strikes the catch 39 at the lower end of said slot and swings the catch away from the wheel 26, and the slot 51 is 50 of such a length that when the vehicle is brought to a stop, the pin 53 contacts with the catch 40 at the lower end of the slot to raise the catch 40 and disengage it from the wheel 26. The caution catch 39 and danger 55 catch 40 are thus controlled by the governor according to the movement of the vehicle, requiring the slowing down of the vehicle to caution speed in order to release the catch 39 and the stopping of the vehicle to release 60 the catch 40.

A safety device is provided for opening the circuit 8 if the magnet 17 fails to be reenergized after the opening of the circuit 8 and reclosing of said circuit between the 65 wheels W and W'. For this purpose, an

electromagnet 54 is disposed in the circuit 8 in series with the magnets 17 and 18, and normally closes a switch 55 between the magnet 21 and the conductor 23', and the magnet 54 is a slow acting one, so that the 70 switch 55 will only be released after an interval of time. Accordingly, if the magnet 17 is deenergized by the opening of the circuit 8 and the circuit is again closed, the switch 55 is held closed during the interval. However, should the magnet 17 become dead 75 and fail to become reenergized to raise the lever 33 so as to turn the ratchet device 19, then after an interval of time sufficient for the magnet 17 to act, the magnet 54 will become dead, thereby releasing the switch 55 and opening the circuit of the magnet 21 to give a danger signal, thereby avoiding the possibility of proceeding with the apparatus 80 out of commission. The magnet 54 will only act if the magnet 17 is not reenergized in the required length of time after being deenergized.

Another precautionary arrangement is the fact that the armature lever 33 and its pawl 34 are a part of the circuit 8, being connected in series with the magnets 17, 18 and 54, and the free terminal of the pawl 34 dips in a cup 56 of mercury or other conducting liquid to close the circuit through said pawl without interfering with the movement of said pawl. Should the lever 33 or pawl 34 be removed, or broken, either accidentally or intentionally, this would immediately open the circuit 8 and produce danger conditions.

A tell-tale or detecting arrangement of the circuit 8 in connection with the insulation 7 is used, whereby the breaking down of the insulation will result in the apparatus giving a danger signal or condition. Thus, the circuit 8 includes the plates 57 embedded in the insulation 7 between the wheels W and W', and said plates are so arranged that a short circuit between the plates or between either plate and the corresponding wheels W or W' will cut off the current from the magnets, thereby letting the equipment go to danger. Thus, the plate 57 of the terminal of the circuit 8 which extends to the wheel W is disposed nearest to the metallic portions in electrical connection with the wheels W', and the other plate 57 is disposed nearest to the frame or other metallic portions in electrical connection with the wheels W, so that a short circuit will assure of a connection between the conductors of the circuit between the generator 16 and the magnets 17, 18 and 54, so that the magnets will be deenergized. In this manner, should the insulation break down, the apparatus will immediately give a danger signal or indication.

The vehicle equipment, as shown in Fig. 1, constitutes a unit or attachment which can 130

be readily installed or applied by attachment to the locomotive or car. It is preferable and convenient to use the rear wheels W of the locomotive for the purposes of the present attachment, which includes the side members 73 secured by suitable means, as at 74, to the bearings or frame members 75 in which the axle 74' of the wheels W is mounted, whereby the members 73 follow in rear of the wheels W and their axle, and the wheels W' are disposed on an axle 75' journaled in the members 73 at the rear ends thereof. The insulated wheels W' are thus located between the wheels of the locomotive and tender, as seen in Fig. 3. The insulation 7 is located in the members 73, to insulate the axles 74' and 75' apart, and the detector plates 57 embedded within the insulation will cause a short circuit of the circuit 8 should the insulation 7 break down between the insulated portions of the carrier members 73. The governor 43, ratchet device 19 and corresponding parts are mounted on a platform 76 supported by the members 73, and are preferably housed within a casing 77. Thus, by embodying the vehicle equipment in such a unit, it can be readily installed by attaching the unit to the rear axle and frame of the locomotive. The casing 77 and other suitable portions of the unit are preferably of insulating material to prevent short circuits from occurring. Such vehicle equipment units can be readily attached to locomotives and cars, by having appropriate attaching means, and such units can be used permanently or as a temporary installation until the equipment can be embodied, if desired, in the structure of the locomotive or car itself. The units will therefore provide, during the course of transition in installing the equipment, temporary installations, although such units may be used as permanent equipment.

Means are provided for maintaining caution controlling conditions of the vehicle, even though the vehicle is slowed down. Thus, the conductors 22 have branches connected to contacts 60 arranged to be engaged by a switch 61 carried by the governor slide 46 when the vehicle is travelling under caution speed, said switch being removed from the contacts 60 when the vehicle is travelling above caution speed. The contacts 60, as shown, are yieldingly supported so as to move downwardly with the switch 61 when the vehicle slows down. Another pair of contacts 62 are connected to the conductors 22 in multiple with the contacts 60, and the contacts 62 are normally engaged by the switch 63 under the influence of an electromagnet 64 which is disposed in one of the conductors 22 between one contact 60 and the corresponding contact 62. The switch 63 is held closed by the magnet 64 which is in series with the magnet 20, and

when the ratchet device 19 is operated one step, the breaking of the circuit of the magnet 20 will also deenergize the magnet 64, thereby releasing the switch 63 and disconnecting the contacts 62. Accordingly, if the vehicle is slowed down to or is travelling at caution speed, whereby the wheel 26 is released and returned to normal position, and the switch 61 engages the contacts 60, to close the auxiliary circuit of the magnet 20, the circuit of the magnet 64 is still open because the switch 63 forms a part of the circuit of the magnet 64 (providing a stick relay) but not of the contacts 60 and magnet 20. Thus, when the vehicle is travelling at caution speed, with the ratchet device restored to normal position, and the circuit of the magnet 20 closed by the switch 61, the vehicle can proceed under caution speed, but should the speed be increased above that permitted, the switch 61 is removed from the contacts 60, thereby opening the circuit of the magnet 20 and again imposing the caution control. Thus, the switch 61 cooperating with the contacts 60 under the control of the governor, will require the travel of the vehicle under caution speed when a caution signal or indication has been given, resulting in the magnet 64 having been deenergized. This condition will be maintained until relieved by the caution-maintaining device as presently described. The auxiliary circuit of the magnet 20 under caution conditions includes the generator 16, conductor 23', magnet 20, conductor 22 leading from said magnet, contacts 60 and switch 61, the other conductor 22, contact 28, segment 27, shaft 31, conductor 22' and part of circuit 8 leading back to generator 16.

The caution-maintaining device includes an electromagnet 65 connected to the circuit 8 to be energized therefrom and fulcrumed, as at 66, for pivotal or oscillatory movement, and having its core extended into an arm 67, which is offset downwardly so as to be disposed close enough to one of the rails of the track, to be attracted thereto against the tension of the spring 68 and the weight of the magnet 65. The magnet 65 carries a switch 69 to engage a contact 70 when the arm 67 is released from its attraction to the rail, and the switch 69 is connected by a conductor 71 (attached to the switch) between the magnet 64 and corresponding contact 62, while the contact 70 is connected by a conductor 72 with the upper or opposite conductor 22. In other words, the switches 69 and 63 are connected in parallel with one another in series with the magnet 64. The core arm 67 of the magnet 65 remains attracted to the rail, thereby holding the switch 69 open, but should the arm 67 and magnet 65 be released from attraction to the rail, the switch 69 will be closed by moving against the con-

70

75

80

85

90

95

100

105

110

115

120

125

130

tact 70, thereby connecting the magnet 64 in the circuit with the magnet 20, so that the magnet 64 is reenergized to attract the switch 63 and again close said switch. The 5 reenergizing circuit for the magnet 64 includes the generator 16, conductor 22', magnet 20, corresponding conductor 22, magnet 64, conductor 71, switch 69, contact 70, conductor 72, the other conductor 22, contact 28, 10 segment 27, shaft 31, conductor 22' and part of circuit 8 leading back to the generator. The switch 63 being closed will complete the circuit of the magnets 20 and 64 without the switch 61, and the vehicle can 15 then be speeded up again, the switch 63 now replacing the switch 61 to complete the circuit of the magnet 20. In order to release the arm 67 and magnet 65 from the rail, the rail is provided therein at a suitable point, 20 such as near the end of the block, with a section 78 of brass or other non-magnetic material, in order that when the arm 67 passes over such non-magnetic section of the rail, it will be released from attraction to the rail and 25 moved by the spring 68 or gravity to close the switch 69 and thus terminate the caution control. It is thus possible to maintain the vehicle under caution control for any given 30 distance of the track, preferably the length of a block, to compel the vehicle to travel under caution speed through a block after a caution signal or indication, the caution control being relieved when the vehicle approaches the end of the block, so that if a 35 clear signal awaits the vehicle in reaching the next block, it can proceed without restriction as to speed.

The caution-maintaining device is a part of the vehicle equipment unit, being disposed within a casing 77' attached to one of the members 73 immediately over the corresponding rail.

A variation is shown in Fig. 12, wherein, instead of using the non-magnetic section of 45 rail, an armature or member 78' of iron or magnetic material is disposed on the track at a suitable point, and the magnet arm 67 is not disposed over the rail or magnetic portion of the track, whereby the arm 67 is 50 normally raised by the gravitation of the magnet 65. In this case, the contact 70 is located above the switch 69 so that the switch is normally down in open position, and when the arm 67 passes over the armature 78', it 55 is attracted downwardly thereto as shown in Fig. 12, thereby raising the switch 69 against the contact 70 and closing the circuit to terminate caution conditions, as above described.

60 A device is provided for removing sand from the rails in advance of the wheels W and W', to prevent the opening of the circuit 8 by the rolling of the wheels W' over the sand. As shown in Fig. 3, the sand 65 applying pipes 80 extend downwardly from

the sand container 79 and terminate in front of the driving wheels 81 for applying the sand to facilitate traction and prevent slipping, and the sand is discharged from the container 79 through the pipes 80 by means of compressed air delivered through a valve 82 from a reservoir 83 to a pipe 84 leading from said valve to the container 79, as well known. The valve being open discharges air into the sand container for blowing the 75 air through the delivery pipes 80. The sand removing device comprises one or more cylinders 85 secured to the frame of the locomotive in rear of the wheels 81 and in advance of the wheels W and W', and said 80 cylinders are connected by a branch pipe 86 with the pipe 84. A piston or plunger 87 is movable in each cylinder, and has a depending scraper 88 projecting from the lower end of the cylinder and provided with a lower rounded end to bear on the rail when the piston is depressed, such piston being normally raised by a coiled spring 89 within the cylinder. The scrapers are thus normally retracted from the rail, but when the 85 valve 82 is opened for discharging sand in front of the wheels 81, air is also admitted to the cylinders 85 to depress the scrapers, whereby they scrape the sand off the rail, and avoiding the insulation of the wheels W' from the rails by sand. In order to assure of sufficient air being delivered to the cylinders 85 to depress the sand scrapers or removers, a pressure valve 90 is preferably 90 disposed in the pipe 84 between the pipe 86 and sand container 79, whereby the air cannot escape through the pipe 84 freely, and assuring of part of the air flowing to the sand removing device. In this manner, simultaneously with the application of sand 100 to the rails, the sand removing device is operated for immediately removing the sand 105 from in rear of the driving wheels, and thereby avoiding the possible opening of the circuit 8 by the presence of sand on the 110 rails.

Each isolated rail section 9 is incorporated in a special insulated rail joint as shown in Figs. 6, 7 and 8. The isolated rail section is disposed between a pair of fish plates 95 the end portions of which overlap the adjacent end portions of the main rail sections, and the fish plates and rail sections are clamped together by means of securing bolts 91, which may be suitably insulated, if desired, in accordance with the other insulation. As shown, the lower flanges of the fish plates have the extension flanges or lips 92 extending under the base flanges of the rail sections, to assist in supporting the joint, and the entire joint may be mounted on a solid base or foundation. The insulation 9' comprises sheets of insulating material located between the fish plates and the rail sections and also between 125 130

the adjacent ends of the rail sections, and detector plates 93 are located between such insulating sheets between the rail sections and fish plates and detector plates 94 are also located between the insulating sheets between the ends of the rail sections. The transverse plates 94 extend between and are connected at their edges to the longitudinal plates 93, whereby such detector plates extend throughout the insulation between the metal parts of the joint, whereby the breaking down of the insulation at any point, will, in establishing a short circuit between the isolated rail section 9 and one of the other rail sections, also create an electrical connection between the detector plates and section 9. This is taken advantage of for giving a signal or indication. A simple arrangement is shown in Fig. 6 including the battery or source of electrical energy 96 having its opposite poles connected to the rail section 9 and detector plates 93, and an electromagnet 97 having its opposite terminals connected to said rail section 9 and detector plates 93, whereby the magnet is ordinarily energized to attract a switch or signal member 98 during normal conditions. However, should the insulation break down, between the rail section 9 and one of the other rail sections, causing an electrical connection of the rail section 9 and detector plates 93, the electrical current will pass through such break-down or short circuit, thereby resulting in the magnet 97 becoming deenergized and the switch or signal member 98 is released to indicate the break down of the insulation, so that repairs can be made.

A typical arrangement of the track circuits is shown in Fig. 10, but other arrangements can be used as may be desired or required, within the scope of what is herein-after claimed, to suit different conditions. In the embodiment of track circuits as shown, such circuits are used with one rail of the track only, but the circuits or part thereof can be duplicated for the other rail also, as will be readily apparent when the circuits are more fully understood. The track circuits of each block are all alike, and Fig. 10 shows one complete block between the semaphores S, with the adjacent ends of the blocks next to such block, and it will be understood that the block to the left has identically the same circuits as for the full block shown, so that the circuits to the left of the left hand semaphore S are the same as those to the left of the right hand semaphore. The circuits of the block to the right of the right hand semaphore are also the same as those to the right of the left hand semaphore. The bridge controlling magnets at the entrance and middle of the block are designated 11 and 11^a, and the isolated rail sections for such magnets are indicated at 9 and 9^a, respectively, each

magnet controlling a bridging switch 10 between the corresponding isolated rail section and conductor 15 connecting the corresponding main rail sections and bridging the insulated joint and isolated rail section. One terminal of the first magnet 11 and the first magnet 11^a are connected by a conductor 100 with a switch 101 under the influence of a magnet 12 of the corresponding semaphore S, and said switch is connected by a conductor 102 with the battery 103 or other source of electrical current. The other pole of the battery is connected by a conductor 104 with a switch 105 and said switch is connected by conductors 106 and 107 with the opposite terminal of the first magnet 11. A switch 108 in the preceding block connects the conductors 106 and 107, just the same as the switch 108 for the block following the full block shown in Fig. 10 is in such full block, and it will be understood that the conductors 106 and 107 of each block are connected by a similar switch 108 in the preceding block. The magnet 12 and a magnet 13 form part of the semaphore device, which may be of any suitable kind, wherein the magnet 12 is deenergized when a caution signal is given, and both magnets 12 and 13 are deenergized when a danger signal is given. The circuit of the first magnet 11^a is completed between the battery 103 and such magnet by means of a conductor 121 connected to the other terminal of the first magnet 11^a, a switch 122 in the block ahead, a conductor 123, and switch 124. Thus, the opening of the switch 101 will open the circuits of both of the first magnets 11 and 11^a, whereas the opening of the switch 108 will open the circuit of the first magnet 11 but not the first magnet 11^a, whereas the opening of either or both of the switches 122 and 124 will open the circuit of the first magnet 11^a but not the first magnet 11.

The second magnet 11 and second magnet 11^a are connected by the respective conductors 109 and 110 with a switch 111 normally closed by the magnet 13, and said switch 111 is connected by the conductor 102 with the battery 103. The other terminal of the second magnet 11 is connected to the conductor 107, the same as the first magnet 11, whereby the circuits of both magnets 11 are controlled by the switch 108 of the block in rear. The conductors 109 and 110 have the respective switches 112 and 113 therein, and the other terminal of the second magnet 11^a is also connected to the conductor 121, so that the circuits of both magnets 11^a are controlled by the switches 122 and 124.

The several circuits of the bridge controlling magnets 11 and 11^a are as follows: One circuit includes the battery 103, conductor 104, switch 105, conductor 106, switch 108 in the block in rear (identically the same as the switch 108 shown in Fig. 10 is for the mag-

nets 11^b of the block ahead), conductor 107, first magnet 11, conductor 100, switch 101 and conductor 102, so that the opening of any one of the switches 105, 108 and 101 would open the circuit of the first magnet 11. Another circuit includes the battery 103, conductor 104, switch 105, conductor 106, switch 108, conductor 107, second magnet 11, conductor 109, switch 112, conductor 110, switch 111, and conductor 102, so that the opening of any one of the switches 105, 108, 112 and 111 would open the circuit of the second magnet 11. Another circuit includes a battery 103, switch 124, conductor 123, switch 122 in the block ahead, conductor 121, first magnet 11^a, conductor 100, switch 101, and conductor 102, so that the opening of any one of the switches 124, 122 and 101 would open the circuit of the first magnet 11^a. Still another circuit includes the battery 103, switch 124, conductor 123, switch 122, conductor 121, second magnet 11^a, switch 113, conductor 110, switch 111, and conductor 102, so that the opening of any one of the switches 124, 122, 113 and 111 would result in the second magnet 11^a being deenergized. The magnets 11 are controlled by a switch 108 in the block in rear, identically the same as the magnets 11^b are controlled by the switch 108 shown in Fig. 10.

The switches 105, 108, 112, 113, 122 and 124 are therefore disposed in the circuits of the bridge controlling magnets for opening the circuits of such magnets and thereby 35 opening the bridges across the insulation of the isolated rail sections should breakdowns in the insulation occur, whereby signals are given and the vehicle controlled notwithstanding the breakdown of an insulated joint and the failure thereof to function. The detector or tell-tale circuits include a battery 115 or other source of electrical energy having conductors 116 and 117 connected to its opposite poles, and the conductor 116 is connected to the detector plates 93 of the isolated rail sections, while the conductor 117 is connected to such isolated rail sections. A magnet 118 controlling the switch 112 has its opposite terminals connected to the first isolated rail section 9 and corresponding detector plate 93, whereby such magnet is normally energized to close the switch 112, when the insulation holds up. Similarly, electromagnets 119 and 120 are 55 connected (in series as shown) with the second isolated rail section 9 and its detector plates 93, and said magnets are thus normally energized to close the respective switches 124 and 122. A magnet 125 has its 60 opposite terminals connected to the first isolated rail section 9^a and the corresponding detector plates, for holding the switch 113 closed, and magnets 126 and 127 are connected (in series as shown) with the second isolated rail section 9^a and corresponding

detector plates 93 for holding the corresponding switches 108 and 105 closed. The magnets 118, 119, 120, 125, 126 and 127 being connected to the detector plates and isolated rail sections, will be connected in circuits with the battery 115 whose lead conductors 116 and 117 are also connected to the detector plates and isolated rail sections, the circuits of the several magnets being readily traced in Fig. 10. Should an insulated joint 70 break down completely so as to leave little or no resistance between the rail sections, then a short circuit would be established, and none of the magnets just referred to would be energized, thereby opening all of the 75 switches controlled by said magnets. However, the break-downs in insulation are not usually complete, so that sufficient resistance would still remain so that only the corresponding magnet would be deenergized 80 while the remaining magnets would be receive sufficient current to keep them energized.

The operation of the apparatus is as follows:—In clear conditions, the switches of 90 the track circuits are all closed, with the bridges across the insulation between the isolated and main rail sections closed, so that the circuit 8 of the vehicle will remain closed as the vehicle passes the isolated rail sections, thereby maintaining the vehicle equipment in clear condition unless there is a failure of current, a short circuit, or the like, which will result in a danger or caution signal. Should the semaphore or 100 other control mechanism be set for caution, the magnet 12 is deenergized to release the switch 101, thereby opening the circuit of the first magnets 11 and 11^a, so that the corresponding switches 10 are opened. Consequently, if the vehicle passes the first isolated rail section 9, the circuit 8 will be 105 opened, thereby deenergizing the magnets 17 and 18 and the lever 33 and pawl 34 will drop. When the wheels W' of the vehicle have passed entirely beyond the first isolated rail sections 9, the circuit 8 is again closed, thereby energizing the magnets 17 and 18, and the lever 33 being raised by the magnet 17 will turn the wheel 26 one 110 step, and the pawl 34 is then removed from the wheel by the magnet 18. The catch 39 will drop into the notch 41 of the wheel 26, to retain said wheel in caution position, with the segment 27 removed from the contact 28, to open the circuit of the magnet 20, so that the armature 24 will drop to give a caution signal or controlling condition. It is then necessary for the vehicle to 115 slow down to caution speed, in order to restore the device 19 by disengaging the catch 39 from the wheel 26. When such caution signal is received by the vehicle equipment, the magnet 64 being deenergized 120 with the magnet 20 releases the switch 63,

thereby maintaining the vehicle under caution control, with the core arm 67 of the magnet 65 attracted to the rail. Such caution control is maintained until the arm 67 is released from the rail by passing over the nonmagnetic section 78 when nearing the end of the block. The releasing of the arm 67 and closing of the switch 69 against the contact 70 will reenergize the magnet 64 to again attract the switch 63, and thereby restore normal conditions.

Under danger conditions, with the magnets 12 and 13 both deenergized and the switches 101 and 111 opened, this will open the circuits of all of the magnets 11 and 11^a, thereby opening both bridges of each pair. Thereby, when the wheels W' pass over the isolated rail sections, the device 19 will be set to caution position by the first breaking and reclosing of the circuit 8, and the wheel 26 is held by the catch 39, and when the circuit is opened and closed the second time, the lever 33 and pawl 34 are released from and again attracted to the magnets 17 and 18, whereby the pawl 34 engages in the notch 36 and advances the wheel 26 a second step so that the catch 40 will drop in the notch 42, thereby retaining the wheel in danger position. The vehicle must then come to a stop in order to remove the catch 40 from the notch 42. Such ratchet device can be under lock and key to avoid tampering therewith or unwarranted release of the controlling conditions, such as when necessary to proceed to the next station for making repairs or adjustments, if the equipment is out of order, or if the danger conditions have been eliminated and the track cleared, or the like.

It will be noted that should the magnet 17 fail to be reenergized to pick up the armature lever 33 for turning the wheel 26 to either position, when the circuit 8 has been broken and closed again, due to the failure of current, short circuit, or the like, the magnet 54, will, after an interval, release the switch 55, thereby opening the circuit of the danger magnet 21 to give a danger signal or condition.

The break down of the insulation 7 will also give a danger signal or condition, as well as the break down of the rail insulation. Thus, should the insulation of the first rail section 9 break down, this would create a short circuit between such rail section and the corresponding detector plates 93, whereby the current from the battery 115 is cut off from the magnet 118, thereby releasing the switch 112 and opening the circuit of the second magnet 11. Accordingly, a caution signal is given when passing the second isolated rail section even though the insulation of the first isolated rail section has broken down. The break down of the insulation of the first rail section 9^a will similarly

deenergize the magnet 125 and release the switch 113, so as to deenergize the second magnet 11^a and open the second bridge at the center of the block. Should the insulation of the second rail section 9 break down, the magnets 119 and 120 will become dead, thereby releasing the switches 124 and 122 which will open. The switch 124 being opened, will open the circuits of both magnets 11^a, thereby providing for a danger signal in the block, by the opening of both of the bridging means for the rail sections 9^a. Furthermore, the switch 122 being opened, will open the circuits of the isolated rail sections in the block preceding, thereby providing for danger signals as the train approaches the broken-down insulation and passes therefrom into the block. Similarly, should the insulation of the second rail section 9^a break down, this will deenergize the magnets 126 and 127 to release the switches 108 and 105. The switch 105 being opened will open the circuits of both magnets 11^a, and the switch 108 being opened will open the circuits of the magnets 11^b of the next block, thereby giving danger signals when the vehicle enters either block. With such an arrangement, the break down of the rail insulation will assure of caution or danger signals being given, and the vehicle cannot therefore proceed without at least receiving the proper signal, and the defect will therefore be quickly noted so that repairs can be made promptly.

A variation in the tell-tale circuits for the rail insulation is shown in Fig. 11, only a simple arrangement being illustrated, although it can be enlarged similar to the arrangement shown in Fig. 10. Thus, the second magnet 11 has its opposite terminals connected by the conductors 130 with the first rail section 9 and its detector plates 93, for connecting said magnet 11 with the conductors 131 which are also connected to the first rail section 9 and its detector plates 93. Thus, a break down of the insulation between the first rail section 9 and other rail sections, will create a short circuit between such rail section 9 and the detector plates 93. This will cut off the current from the magnet 11, which will therefore open the corresponding bridge. With this arrangement, the same as in the one shown in Fig. 10, the breaking of a conductor or connection will also open the detector circuits in the same way.

Having thus described the invention, what is claimed as new is:—

1. Vehicle controlling apparatus including main rail sections, an isolated rail section between them, fish plates secured to the adjacent end portions of the main rail sections and supporting the isolated rail section between them, insulation between the rail sections and fish plates, detector plates in said

insulation, and a detector circuit including the isolated rail section and detector plates.

2. Vehicle controlling apparatus including a rail having a plurality of insulated joints, bridging means for said joints adapted to be opened and closed, and means whereby the breaking down of the insulation of a joint will open the bridge of another joint.

3. Vehicle controlling apparatus including a rail having a plurality of insulated joints, bridging means for the joints, a vehicle circuit normally closed by the rail and opened when passing said joints with the bridging means open, and an electrical detector circuit for each joint and controlling the bridging means of another joint whereby the breaking down of the insulation of the corresponding joint will open the bridge of the other joint.

4. Vehicle controlling apparatus including a rail having a plurality of insulated joints for breaking a vehicle circuit, bridging means for said joints adapted to be opened and closed, detector plates embedded in the joints, and a detector circuit for each joint including the corresponding detector plate and controlling the bridge of another joint to open such bridge should the insulation break down.

5. Vehicle controlling apparatus including a rail having a plurality of insulated joints for breaking a vehicle circuit, bridging means for said joints adapted to be opened and closed, electromagnets for maintaining said bridging means closed, and electrical connections for each joint including the magnet of another joint whereby the breaking down of the insulation will result in such magnet being deenergized for opening the bridge of the other joint.

6. Vehicle controlling apparatus including a rail having a plurality of insulated joints, for controlling a vehicle circuit, switches for bridging said joints, electromagnets for holding said switches closed, detector plates embedded in said joints, and an electrical circuit for each joint including the corresponding detector plate and controlling the magnet of another joint whereby the breaking down of the insulation will result in such magnet being deenergized to open the switch of the other joint.

7. Vehicle controlling apparatus embodying a rail having insulated joints, bridges for said joints, and means so arranged that when the insulation of one joint breaks down the bridge of another joint is opened.

8. Vehicle controlling apparatus including a rail having insulated joints for controlling a vehicle circuit, a bridge for each joint, electromagnets for holding the bridges closed, and a detector plate in one joint forming part of a circuit controlling the magnet of another joint for the deenergiza-

tion of such magnet should the detector plate form part of a short circuit in the corresponding joint.

9. Vehicle controlling apparatus including a unit for attachment to a locomotive to follow in rear thereof in front of the tender and having a contact member to engage a rail of the track, insulation for insulating said contact member from the locomotive, a vehicle circuit including said contact member and a portion of the locomotive to be completed by the rail and to be broken by insulated joints in the rail, said unit also including a responsive device in said circuit and governor controlled means for said device connected to an axle of the locomotive.

10. Vehicle controlling apparatus including a vehicle equipment unit for attachment to a locomotive to follow in rear thereof in front of the tender and having a contact member to travel on a rail of the track, insulation for insulating said contact member from the locomotive, responsive means connected in circuit with said contact member and a portion of the locomotive for the breaking of the circuit in passing an insulated joint of the rail, a governor operated from an axle of the locomotive and means for controlling said responsive means from the governor.

11. Vehicle controlling apparatus including a vehicle equipment having a contact member to bear on a rail for completing a vehicle circuit, sand removing means in advance of said member comprising a cylinder, a piston working in said cylinder, a scraper carried by the piston to bear on the rail, and means for admitting pressure fluid into said cylinder.

12. Vehicle controlling apparatus including in combination with sand applying means, a vehicle equipment having a contact member to travel on a rail of the track for closing a vehicle circuit, means operable for removing the sand from the rail in rear of the sand applying means and in advance of said contact member, and operable simultaneously with the sand applying means.

13. Vehicle controlling apparatus including in combination with the air pressure sand applying means of a vehicle including a valve and a pipe for delivering the sand to a rail of the track, of a vehicle controlling equipment including a contact member to bear on the rail in rear of said pipe for controlling a vehicle circuit, and a pneumatic sand remover having a scraper to be moved against the rail between said pipe and contact member, and a connection between the sand remover and sand applying means for operating the sand remover simultaneously with the application of sand.

14. Vehicle controlling apparatus including a rail having a plurality of isolated

insulated sections for controlling a vehicle circuit, switches for bridging the isolated and main rail sections across the insulation, electromagnets for holding said switches

5 closed, detector plates embedded in the insulation between the isolated and main rail sections, and an electrical circuit for each isolated rail section including the corresponding detector plate and controlling the 10 magnet of another isolated rail section whereby the breaking down of the insulation will result in such magnet being deenergized to open the switch of the other isolated rail section.

15 15. Vehicle controlling apparatus embodying a rail having isolated insulated sections, bridges for connecting the isolated and main rail sections across the insulation, and means so arranged that when the insulation of one 20 isolated rail section breaks down, the bridge of another isolated rail section is opened.

16. Vehicle controlling apparatus including a rail having isolated insulated rail sections for controlling a vehicle circuit, a bridge for each isolated rail section to connect it with the main rail sections across the insulation, electromagnets for holding the bridges closed, and a detector plate in the insulation of one isolated rail section 25 forming part of a circuit controlling the magnet of another joint for the deenergization of such magnet should the detector

plate form a part of a short circuit in the corresponding isolated rail section joint.

17. Vehicle controlling apparatus including a rail or conductor having insulated isolated sections and main sections, controlled bridges for connecting the isolated and main sections across the insulation, and a vehicle controlling equipment including a circuit 35 normally closed by said rail or conductor and having a contact member to pass over said isolated sections and to open the circuit one or more times when the bridges are opened, and means operated by the breaking and closing of said circuit one or more times for producing progressive controlling conditions.

18. Vehicle controlling apparatus including a magnetic rail, a vehicle controlling 40 circuit normally closed by said rail, said rail having insulated portions for opening said circuit, means for bridging said insulated portions to prevent the opening of said circuit, means controlled by said circuit for 45 producing predetermined controlling conditions, means for maintaining such conditions including a magnetic member attracted to said rail, and a non-magnetic section in said rail for releasing said member to 50 relieve said conditions.

In testimony whereof I hereunto affix my signature.

ALFRED L. RUTHVEN.
